(57) CLAIM

The ornamental design for a shoe, as shown and described.

DESCRIPTION

FIG. 1 is a bottom view of a shoe showing my new design;
FIG. 2 is a bottom rear perspective view thereof; and
FIG. 3 is an enlarged view of the claim as shown in FIG. 2 with environment removed for clarity purposes.
The broken line immediately adjacent to and surrounding the shaded area defines the peripheral bounds of the claimed design and forms no part thereof. The broken lines depicting the remainder of the shoe form no part of the claimed design.1 Claim, 3 Drawing Sheets(56)
